(57) **CLAIM**

The ornamental design for a vehicle mirror, as shown and described.

DESCRIPTION

FIG. 1 is a perspective view of a right vehicle mirror (the left vehicle mirror being similar to the right and is not illustrated);

FIG. 2 is a front elevational view of the vehicle mirror;

FIG. 3 is a left elevational view of the vehicle mirror;

FIG. 4 is a right elevational view of the vehicle mirror;

FIG. 5 is a top plan view of the vehicle mirror;

FIG. 6 is a bottom plan view of the vehicle mirror; and,

FIG. 7 is a rear elevational view of the vehicle mirror.

The second embodiment is a mirror image of the right vehicle mirror as shown in FIGS. 1-7.

Shading is used to illustrate the curvature of the part and not color. Areas shown in or bounded by broken lines are not claimed. Views are orthogonal projections unless otherwise noted. The various views are not necessarily to scale in order to better illustrate the design.
